DESIGN FOR A FRINGED TEXTILE FABRIC

Samuel H. Geffner, New York, N. Y.

Application October 2, 1937, Serial No. 71,922

Term of patent 3½ years

To all whom it may concern:

Be it known that I, Samuel H. Geffner, a citizen of the United States, residing at Manhattan, in the county of New York and State of New York, have invented a new, original, and ornamental Design for a Fringed Textile Fabric, of which the following is a specification, reference being had to the accompanying drawing, forming part thereof.

In the drawing, the figure represents a plan view of the fringed textile fabric.

I claim:

The ornamental design for a fringed textile fabric, as shown.

SAMUEL H. GEFFNER,
